SHIPPING INSECTICIDE CONTAINER SPRAY GUN

Original Filed Sept. 13, 1926 2 Sheets-Sheet 2

UNITED STATES PATENT OFFICE.

FRANK D. PELOT, OF DALLAS, TEXAS.

SHIPPING INSECTICIDE-CONTAINER SPRAY GUN.

Application filed September 13, 1926, Serial No. 135,097. Renewed July 29, 1927.

The invention has for its primary object the provision of a unitary structure for marketing a liquid insecticide and admitting of the purchaser using the device for spraying the insecticide in the accustomed way.

The invention furthermore aims to supply a device embodying a container and spray gun which may be marketed with the container filled with a liquid insecticide and sealed to prevent the escape of the contents, thereby supplying to the trade a combined spray gun and filled container at a cost slightly in excess of either when purchased singly, besides insuring both being at hand when it is required to distribute the insecticide.

The invention also aims to supply a combined shipping container and spray gun for a liquid insecticide having bodies formed from a single blank of sheet metal so connected as to mutually strengthen and brace each other.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a perspective view of a combined shipping container and spray gun for a liquid insecticide embodying the invention.

Figure 2 is a vertical, central, longitudinal sectional view of the device.

Figure 3 is a transverse sectional view on the line 3—3 of Figure 2, looking in the direction of the arrows.

Figure 4 is an enlarged detail sectional view of portions of the bodies of the container and spray gun, showing the intermediate connection.

Figure 5 is an enlarged detail sectional view of the delivery end of the spray gun, showing more clearly the closure for the delivery, or spray tube, and

Figure 6 is a detail view of the blank from which the bodies of the container and spray gun are formed, including the intermediate connection, the dotted lines indicating the creases or folds.

Corresponding and like parts are referred

to in the following description and designated in the several views of the drawings by like reference characters.

The numeral 1 designates the body of the container in which the liquid insecticide is shipped, said body being preferably of cylindrical form and closed at opposite ends, one of which has a filling opening which is closed by means of a screw cap 2. A baffle 3 is located a short distance from the delivery end of the container and forms a chamber 4 which is adapted to hold a quantity of a liquid insecticide so that the device may be successfully used in an elevated position after the contents have been partly drawn off from the container 1. The delivery, or spray tube 5, passes through the delivery end of the container 1 and terminates a short distance from the bottom of the chamber 4.

The body of the spray gun is designated by the numeral 6 and the same is preferably of cylindrical form and of a length coextensive with the container 1. The body 6 is closed at both ends, the delivery end having a small opening 8 for the discharge of a blast of air, whereby the liquid insecticide is drawn from the container 1 through the tube 5 and delivered in the form of a spray in a manner well understood. A piston 7 located within the body 6 is adapted to be reciprocated therein by means of a rod 9 which passes through an opening in the end of the gun opposite that provided with the air outlet 8. The tube 5 has an end portion extending along the delivery end of the spray gun and terminating adjacent the air outlet 8 to admit of the jet of air discharged through the outlet 8 passing across the extremity of the tube, whereby to effect a delivery of the insecticide in the form of a spray.

The bodies of the container 1 and spray gun 6 are united by an intermediate connection 10 and the several parts are formed from a single blank substantially as shown in Figure 6. The part 10 is provided with folds 11 and reverse folds 12 beyond the folds 11. The folds 11 provide pockets which face in the same direction and receive marginal edge portions of the blank after the same has been rolled to provide the cylindrical bodies corresponding to the parts 1 and 6. The edge portions of the blank, after being inserted within the folds 11, are made secure by solder, or in any other preferred way common in the sheet metal art. The edge portions are offset, as indicated at 13, to correspond with the

5 folds 12 so that the inner walls of the cylindrical body may be practically continuous and smooth. The sheet metal blank is designated generally by the numeral 14 and is of a rectangular outline, and the several folds corresponding to the parts 11, 12 and 13 are indicated by the dotted lines in Figure 6.

10 The delivery end of the spray tube 5 is internally threaded and receives the threaded portion 15 of a closure 16. A milled head 17 is formed upon the outer end of the closure 16 and the inner end of the closure is reduced, as indicated at 18, to provide in effect a needle valve for sealing the tube 5. The closure 16 15 consists of a short rod or stem, and is connected to the device by means of a short chain 19, or other suitable connection to prevent loss or misplacement of the closure, when removed from the tube 5.

20 It is observed that the container 1 is supplied with the liquid insecticide and escape thereof is prevented by applying the cap 2 to the filling opening and the closure 16 to the delivery end of the spray tube 5, thereby admitting of the device being shipped and marketed in condition for instant use by the purchaser. It is observed that the container and the spray gun are always at hand for instant use, without liability of misplacement, 25 as frequently occurs when the gun and container consist of separate parts. The part 10, besides forming connecting means between the two cylindrical bodies, serves to reinforce and brace the same. The container also 30 serves as a convenient handle when using the device for spraying the insecticide. When the container 1 holds a small quantity of insecticide, it may be tilted to supply the chamber 4, thereby admitting of the device 35 being elevated when it is required to deliver a spray at an elevation, as is frequently necessary.

Having thus described the invention, I claim:

45 1. A device of the character described comprising a container and a spray gun, the bodies of both being formed from a single blank having intermediate portions folded to provide a spacing web and pockets along 50 opposite sides of the web, each pocket having opposed walls and being open along a side, the end portions of the blank being each curved upon itself to form a cylindrical body and having its marginal edge secured within 55 the cooperating pocket at the adjacent side of the web between the opposed walls thereof.

2. A device of the character described comprising a container and a spray gun, the bodies of both being formed from a single blank having intermediate portions folded 60 to provide a spacing web and pockets extending along opposite sides of the web and each open along one side, the end portions of the blank being folded back against the pockets and each curved upon itself to form a cylindrical body unobstructed throughout its length and having its longitudinal marginal edge portion fitted into the cooperating pocket along the adjoining side of said web and secured in the pocket. 70

3. A device of the character described comprising a container and a spray gun, the bodies of both being formed from a single blank having intermediate portions folded to provide a spacing web and pockets along 75 opposite sides of the web extending transversely thereof and each having opposed walls and open along a side adjoining the web, the end portions of the blank being each curved upon itself to form a cylindrical body and having its marginal edge portion bent to provide an abutment shoulder and a tongue 80 projecting therefrom in offset relation to the body, said tongue being fitted into the pocket at the adjoining side of said web and firmly 85 secured therein with the shoulder bearing against a wall of the pocket.

4. A device of the character described comprising a container and a cooperating spray gun, each having a substantially cylindrical body, the bodies being spaced transversely from each other with their forward ends in substantially the same plane, a connecting web extending between said bodies radially thereof and rigid therewith and 90 having its forward end terminating substantially flush with the ends of the bodies, heads for the front and rear ends of said bodies, the head at the front end of said gun having an air outlet opening formed therein, a discharge tube leading from the container through the head at its front end and extending along the forward edge of said web and outer face of the forward head of said gun in contacting engagement therewith and terminating adjacent the outlet thereof, and means to discharge air from said gun through its outlet across the outer end of said tube. 100

In testimony whereof I affix my signature.

FRANK D. PELOT. [L.S.]
